UNITED STATES PATENT OFFICE.

OTTO S. PIKE, OF MALDEN, MASSACHUSETTS, ASSIGNOR TO AMERICAN PNEUMATIC SERVICE COMPANY, OF DOVER, DELAWARE, A CORPORATION OF DELAWARE.

PNEUMATIC-DESPATCH-TUBE APPARATUS.

SPECIFICATION forming part of Letters Patent No. 790,456, dated May 23, 1905.

Application filed February 12, 1904. Serial No. 193,233.

To all whom it may concern:

Be it known that I, OTTO S. PIKE, of Malden, in the county of Middlesex and State of Massachusetts, have invented certain new and useful Improvements in Pneumatic-Despatch-Tube Apparatus, of which the following is a specification.

My invention relates to improvements in receiving-terminals for pneumatic-despatching apparatus; and its object is to provide means for removing a carrier from the pneumatic transmission-tube without allowing air from the transmission-tube to escape into the atmosphere violently.

Another object of my invention is to provide means whereby the carriers may be brought entirely into the receiving-chamber promptly and automatically and promptly discharged therefrom.

The terminal consists, essentially, of a receiving-chamber forming a continuation of the transmission-tube, a valve between the receiving-chamber and the transmission-tube, a valve between the receiving-chamber and the atmosphere; and mechanism for operating the valves.

My invention consists of certain novel features hereinafter described, and particularly pointed out in the claims.

In the accompanying drawings, which illustrate a construction embodying my invention, Figure 1 is an elevation of the terminal with valves and mechanism in their normal positions. Fig. 2 is a plan view of the same. Fig. 3 is an elevation, partly in section, showing valves and mechanism in position for discharging a carrier from the terminal. Fig. 4 is a section through the receiving-chambers and valves when the valves are in their normal position. Fig. 5 is a similar view showing the valves in position for discharging a carrier. Fig. 6 is a section through the piston slide-valve and auxiliary cylinder, hereinafter described, showing parts in their normal positions. Fig. 7 is a horizontal section through the piston slide-valve, showing the same in the opposite position to that shown in Fig. 6.

Like letters of reference refer to like parts throughout the several views.

A is the end of the transmission-tube, the arrow-head B showing the direction in which the carrier travels.

A³ is a grated T, having the ports A⁵, leading from its interior into the annular space A⁶ surrounding. The air coming through the tube A passes through the ports A⁵ into the annular space A⁶ and thence into the pipe A⁴.

A' is a receiving-chamber forming a continuation of the transmission-tube and normally closed to the atmosphere by the valve A⁷.

A² is a valve interposed between the receiving-chamber A' and the T A³ and normally open.

Valves A² and A⁷ are so constructed that when their axes are placed in line with the axis of the receiving-chamber A' carriers can pass through them freely. Valves A² A⁷ are suitably mounted on trunnions, the front trunnions being attached to the cranks A⁸ A⁹, respectively. The crank A⁸ is connected to the bell-crank A¹⁰ by the connecting-rod B'. The crank A⁹ is connected to the bell-crank B² by the connecting-rod B³. The bell-cranks A¹⁰ and B² are operated by rollers B⁴ and E, respectively mounted on the wrist-plate B⁵ and working between the jaws B⁶ and B⁷ of the bell-cranks A¹⁰ and B², respectively. The wrist-plate B⁵ is in turn actuated by the piston B⁸ in the cylinder B⁹, the piston B⁸ being connected to the wrist-plate B⁵ by the piston-rod B¹⁰ and the connecting-rod C. The piston B⁸ is operated by a supply of compressed air or other fluid admitted to the cylinder B⁹ through the pipes C' or C².

The supply of compressed air above referred to is controlled by the piston slide-valve C³ in the valve-chest C⁴, Fig. 6. This valve-chest C⁴ is fitted with ports C⁵ C⁶, leading to the pipes C² and C', respectively. The construction of the slide-valve C³ and valve-chest C⁴ is well known in the art.

The supply of compressed air for operating the mechanism is introduced into the valve-

chest C⁴ through the pipe C⁷ from any suitable source. Attached to the valve-chest C⁴ is an auxiliary cylinder C⁸, Fig. 6. In this cylinder C⁸ is an auxiliary piston C⁹, and attached 5 to the piston C⁹ is the piston-rod C¹⁰. The valve C³ is pushed to the right by the piston C⁹, as hereinafter described. The valve C³ is pushed to the left by the rod D, Figs. 1, 2, and 3, which is attached to the finger D', this 10 finger being operated by the carrier D² as the latter is discharged from the terminal. From the right-hand end of the auxiliary cylinder C⁸ the pipe D³ is led into the annular space A⁶ of the T A³. The pipe D⁴ leads from the 15 receiving-chamber A' at a point near the valve A⁷ to the left-hand side of the piston C⁹ in the cylinder C⁸. When the carrier arrives at the terminal and after it has passed the ports A⁵ in the T A³, a cushion of compressed 20 air is formed in the chamber A' by the energy of the carrier. In order to prevent this air-cushion from stopping the carrier in the terminal before the carrier has passed entirely through the valve A², the pipe D⁵ is led from 25 a point in the chamber A' near the valve A⁷ into the annular space A⁶ of the T A³. In the pipe D⁵ is a valve D⁶, which controls the amount of air which may flow through the pipe D⁵. The check-valve D⁷ in the pipe D⁵ 30 opens in the direction of the arrow D⁸, and while it allows air to flow readily from the chamber A' to the T A³ it prevents any flow in the opposite direction. By partially or wholly opening the valve D⁶ part or whole of 35 the air-cushion formed by the arriving carrier is destroyed by the air escaping through the by-pass pipe D⁵, thus allowing the carrier to be forced entirely through the valve A² by its momentum. As the carrier advances 40 into the valve A² and receiving-chamber A' the pressure generated in front of the carrier passing through the pipe D⁴ forces the piston C⁹ in the cylinder C⁸ to the right, carrying with it the piston-valve C³. 45 This allows compressed air from the pipe C⁷ to pass through the port C⁶ into the pipe C', thence to the left of the piston B⁸ in the cylinder B⁹. This supply of compressed air forces the piston B⁸ to the right, at the same 50 time moving the wrist-plate B⁵ a portion of a revolution. During the first portion of this movement the bell-crank A¹⁰ is revolved by means of the roller B⁴ working in the jaws B⁶ of the bell-crank A¹⁰, thus revolving the valve A² from the position shown in Fig. 4 to that 55 shown in Fig. 5. As the valve A² reaches this position the roller B⁴ disengages from the jaws B⁶ of the bell-crank A¹⁰ and the locking-arc D⁹, mounted on the wrist-plate B⁵, engages 60 with the curved portion D¹⁰ of the bell-crank A¹⁰ and locks the bell-crank A¹⁰ in position. During the motion of the bell-crank A¹⁰ the bell-crank B² is similarly locked by the locking-arc D⁹. As the roller B⁴ disengages from the

jaws B⁶ the roller E engages the jaws B⁷ of 65 the bell-crank B², and during the latter part of the movement of the wrist-plate B⁵ the valve A⁷ is opened into the position shown in Figs. 3 and 5. Leading from the T A³ to a point in the receiving-chamber A' on the 70 right and close to the valve A² is a pipe E'. In this pipe E' is a check-valve E², which allows the air to pass in the direction shown by the arrow E³, but not in the opposite direction. As the valve A⁷ opens, as above described, the pressure in the receiving-chamber A' escapes into the atmosphere. The 75 pressure in the transmission-tube A causes the air to flow through the pipe E' behind the carrier in the receiving-chamber A', and this 80 forces the carrier out through the valve A⁷ into the receiving-trough E⁴. As the carrier slides along the trough E⁴ it strikes the finger D' and forces the piston-valve C³ to the left, as above described. This allows compressed 85 air from the pipe C' to pass into the port C⁵ and thence through the pipe C² to the right of the piston B⁸, thus forcing the piston B⁸ to the left into its normal position, the valve A⁷ closing and the valve A² opening successively 90 in a manner similar to their opposite motions as described above, and thus restoring the valves to their normal positions, Fig. 5. When the piston B⁸ moves to the right, as 95 previously described, the air on the right of the piston is exhausted into the atmosphere through the pipe C², port C⁵, and through the opening E⁵ in the valve-chest C⁴. Similarly when the piston B⁸ moves to the left the air to the left of the piston is exhausted into the 100 atmosphere through the pipe C', the port C⁶, and the opening E⁶ in the valve-chest C⁴. As a carrier passes by the finger D' or when a carrier is removed from the trough E⁴ said finger D' is forced back to its normal position, 105 as shown in Fig. 1, by the spring E⁶ on the rod D.

The air from the pipe C⁷ is prevented from escaping directly into the atmosphere by the piston slide-valve C³, which compels the air 110 from said pipe C⁷ to pass into the pipe C' or pipe C², according as the piston slide-valve C³ is in the right-hand or left-hand position. (See Figs. 6 and 7.) The air from the pipe C⁷ passes through the pipe C' or C² to the cylinder B⁹, as before described. 115

Having thus described the nature of my invention and set forth a construction embodying the same, what I claim as new, and desire to secure by Letters Patent of the United 120 States, is—

1. In an apparatus of the character described, a transmission-tube, a terminal, a receiving-chamber in said terminal, a valve between said transmission-tube and said receiving-chamber, a valve between said receiving-chamber and the atmosphere, and a pipe establishing communication between 125

said receiving-chamber and said transmission-tube for relieving the air-cushion ahead of the carrier in the receiving-chamber.

2. In an apparatus of the character described, a transmission-tube, a terminal, a receiving-chamber in said terminal, a valve between said transmission-tube and said receiving-chamber, a valve between said receiving-chamber and the atmosphere, a pipe establishing communication between said receiving-chamber and said transmission-tube for relieving the air-cushion ahead of the carrier in the receiving-chamber, and a valve controlling the current of air flowing through said pipe.

3. In an apparatus of the character described, a transmission-tube, a terminal, a receiving-chamber in said terminal, a valve between said transmission-tube and said receiving-chamber, a valve between said receiving-chamber and the atmosphere, a pipe establishing communication between said receiving-chamber and said transmission-tube for relieving the air-cushion ahead of the carrier in the receiving-chamber, and a valve in said pipe allowing the flow of air from the receiving-chamber to the transmission-tube and preventing the flow of air from the transmission-tube to the receiving-chamber.

30 4. In an apparatus of the character described, a transmission-tube, a terminal, a receiving-chamber in said terminal, a valve between said transmission-tube and said receiving-chamber, a valve between said receiving-chamber and the atmosphere, a pipe establishing communication between said receiving-chamber and said transmission-tube for relieving the air-cushion ahead of the carrier in the receiving-chamber, a valve controlling the current of air flowing through said pipe, and a valve in said pipe allowing the flow of air from the receiving-chamber to the transmission-tube and preventing the flow of air from the transmission-tube to the receiving-chamber.

45 5. In an apparatus of the character described, a terminal, a transmission-tube, a valve between the transmission-tube and the receiving-chamber and normally open, a valve between the receiving-chamber and the atmosphere and normally closed, mechanism common to said valves for operating the same, a cylinder, a piston in said cylinder connected to said mechanism, an air-supply

for operating said piston to move said valves, and mechanism in the line of travel of the carrier and actuated thereby for operating said valve-operating mechanism to return said valves to their normal positions.

6. In an apparatus of the character described, a terminal, a transmission-tube, a valve between the transmission-tube and the receiving-chamber and normally open, a valve between the receiving-chamber and the atmosphere and normally closed, mechanism common to said valves for operating the same, a cylinder, a piston in said cylinder connected to said mechanism, an air-supply for operating said piston to move said valves, mechanism in the line of travel of the carrier and actuated thereby for operating said valve-operating mechanism to return said valves to their normal positions, and means for returning said carrier-operated mechanism to its normal position.

7. In an apparatus of the character described, a terminal, a transmission-tube, a valve between the transmission-tube and the receiving-chamber and normally open, a valve between said receiving-chamber and the atmosphere and normally closed, a pipe for leading air in the transmission-tube from one side of the valve between the receiving-chamber and the transmission-tube for forcing a carrier from the terminal.

8. In an apparatus of the character described, a terminal, a transmission-tube, a valve between the transmission-tube and the receiving-chamber and normally open, a valve between said receiving-chamber and the atmosphere and normally closed, a pipe for leading air in the transmission-tube from one side of the valve between the receiving-chamber and the transmission-tube for forcing a carrier from the terminal, and a check-valve in said pipe allowing a flow of air from the transmission-tube to the receiving-chamber and preventing a flow of air from the receiving-chamber to the transmission-tube.

In testimony whereof I have signed my name to this specification, in the presence of two subscribing witnesses, this 4th day of February, A. D. 1904.

OTTO S. PIKE.
